UNITED STATES PATENT OFFICE.

THEODORE SCHREINER, OF BROOKLYN, NEW YORK.

COLLAPSIBLE DRUM.

1,113,253.

Specification of Letters Patent.

Patented Oct. 13, 1914.

Application filed May 13, 1913. Serial No. 767,467.

To all whom it may concern:

Be it known that I, THEODORE SCHREINER, a citizen of the United States, residing at Brooklyn, in the county of Kings and State of New York, have invented certain new and useful Improvements in Collapsible Drums, of which the following is a specification.

This invention relates broadly to the class of musical instruments and more particularly to drums.

The primary object of the invention contemplates the provision of a foldable or collapsible drum wherein the drum ends or heads may be telescoped one within the other so that the drum during shipment will occupy only a minimum amount of space, and will, when collapsed, facilitate the handling of the drum when not in use.

A further object of the invention resides in the provision of novel and peculiar means including a plurality of spaced apart bars or rods detachably arranged upon the periphery of the drum body, the removal of which will allow the said drum to be folded or collapsed should occasion demand.

A still further object of the invention is to create a shipping receptacle out of the drum body, and to provide the said body with an opening or doorway leading thereinto, this admitting the insertion or incasement of a smaller drum or other musical instrument into the interior of the drum body during the shipment or conveyance of the latter.

The collapsible feature is particularly desirable in the larger sizes of drums, such as are commonly known as "bass-drums."

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein like characters denote like or corresponding parts throughout the several views, and in which:

Figure 1 is an elevation of a drum constructed in accordance with my invention; Fig. 2 is a similar view, the drum being shown in collapsed condition; Fig. 3 is a longitudinal sectional view, partly broken away; Fig. 4 is a similar view, in collapsed

condition; and, Fig. 5 is a detail perspective view of one of the spacing bars.

Referring now more particularly to the drawings, wherein is illustrated the preferred embodiment of my invention, the numeral 1 designates the body of the drum, which is formed of any suitable flexible material such as sheep-skin or the like, and which is adapted when adjusted, to form a body of the proper shape between the drum heads 2 of the instrument. The drum heads 2 are each secured to a suitable flesh-hoop 3 in the usual manner over and upon which a retaining-hoop 4 is passed for holding the said flesh-hoop in the desired position to retain the drum heads under tension. Adjacent each retaining-hoop and within the flesh-hoop 3 I provide a pair of body retaining-hoops 5, the latter serving the double purpose of supporting the said heads 2 in the desired position and retaining the flexible material of which the body is composed in drawn or in tight condition during operation of the instrument for the purpose for which it is designed. Any suitable means such as the usual fastening mechanism shown at 6 may be employed for tightening the heads 2 upon the drum.

Having described in detail the manner in which the drum proper is constructed, the collapsible feature will now be fully set forth. Arranged upon the periphery of the body portion in uniform spaced relation, I provide a plurality of spacing bars 7, the upper extremity of the said bar being provided with a notch 8 adapted to receive suitable pins 9 secured to the periphery of the upper body retaining band or hoop 5, while the lower extremity of the said bar 7 is also provided with a notch 9' disposed at one side thereof, the said notch 9 adapted to likewise receive a pin 10 projecting from the periphery of the lower body retaining band, where it is held through the medium of a thumb-nut 11, the operation or tightening of which will effect a secure clamp connection between the said bar 7 and the lower band 5.

A removable door 12 is secured to the body 1 by means of a plurality of buttons 13, the said buttons adapted to fit within suitable holes 14 formed within the said door. An opening 15 is provided within the drum body 1 beneath the said door 12 to permit the insertion or storage of either a smaller drum or other musical instru-

ments within the interior of the drum body when it is desired that the drum should be used for that purpose. Any suitable hinge connection such as is designated as at 16 5 may be afforded for the said door 12.

One of the drum heads 2 is made smaller than the other one so as to permit the said heads, when the drum is folded to telescope or fit one within the other, this arrangement 10 of the two drum sections or heads bringing the same into close proximity and facilitating the shipping and the handling of the drum when not in use.

To collapse or fold the drum, the thumb-nut 11 is loosened sufficiently upon the pin 10 to permit movement of the bar 7 so as to withdraw the lower end of the said bar from engagement with the said pin 10, whereupon the notch 8 formed within the 20 upper end of the said bar may be disengaged from the pin 9 of the upper band. The removal of all of said bars in the manner above described will allow the drum body to completely collapse or telescope as 25 is shown in Fig. 4 of the drawings, thus materially reducing the size of the drum and facilitating the conveyance or shipment of the drum from place to place.

By the provision of the opening 15 of the 30 drum body, it will be seen that the interior of the drum may be used as a storage receptacle capable of fully protecting any musical or other instrument that may be contained therein.

In reduction to practice, I have found that the form of my invention, illustrated in the drawings and referred to in the above description, as the preferred embodiment, is the most efficient and practical, yet realizing 40 that the conditions concurrent with the adoption of my device will necessarily vary, I desire to emphasize the fact that various minor changes in details of construction, proportion and arrangement of parts may 45 be resorted to, when required, without sacrificing any of the advantages of my invention, as defined in the appended claims.

Having thus fully described my invention, what I claim as new and desire to set 50 cure by Letters Patent is:—

1. In a collapsible drum, the combination with a pair of drum heads, one of which is of smaller diameter than the other, of a flexible body portion connecting said drum heads, a plurality of peripherally arranged spacing and bracing rods to normally hold said drum heads in a separated position, a plurality of pins carried by said drum heads

to coact with said rods, longitudinal notches being formed in the upper end of each rod 60 to seat the adjacent pins and prevent collapse of said drum heads, transverse notches being formed in the lower end of each rod to facilitate the removable positioning of said rods and to similarly coact with adjacent pins, and means preventing casual lateral displacement of said rods at their lower ends.

2. In a collapsible drum, the combination with a pair of drum heads of different 70 diameters capable of a telescopic action together, of a flexible body portion connecting said drum heads to permit such telescopic action and to prevent undue separation of the heads, and means for wedging said drum 75 heads apart to their limit of separation, said means including a plurality of peripherally arranged pins carried by said drum heads, and a plurality of bracing rods, each rod being formed at its upper end with a longitudinal notch for engaging the adjacent pin preparatory to wedging said rods in position, and each rod being further formed at its opposite extremity with a transverse notch for the lateral reception of a proper 80 pin, and means preventing casual lateral displacement of said rods.

3. In a collapsible drum, the combination with a pair of drum heads of different 90 diameters capable of a telescopic action together, of a flexible body portion connecting said drum heads to permit such telescopic action and to prevent undue separation of the heads, and means for wedging said drum 95 heads apart to their limit of separation as determined by said body portion, said means including a plurality of peripherally arranged pins carried by each of said drum heads, and a plurality of bracing rods, flanges formed upon each of said rods at the 100 ends thereof, each upper flange being provided with a longitudinal notch for engaging the adjacent pin preparatory to wedging said drum heads in their separated position, and each lower flange being formed with a 105 transverse notch for the lateral reception of a proper pin, and means preventing casual lateral displacement of said rods at their lower ends.

In testimony whereof I affix my signature 110 in presence of two witnesses.

THEODORE SCHREINER.
